[57] **CLAIM**

The ornamental design for a device for maintaining a gasoline pump nozzle in the open position, as shown and described.

DESCRIPTION

FIG. 1 is a perspective view of a device for maintaining a gasoline pump nozzle in the open position showing my new design;

FIG. 2 is a right side elevational view thereof;

FIG. 3 is a left side elevational view thereof;

FIG. 4 is a bottom plan view thereof;

FIG. 5 is a top plan view thereof;

FIG. 6 is a front elevational view thereof;

FIG. 7 is a rear elevational view thereof.

The chain which is shown in FIG. 1 has been omitted from FIGS. 2-7 for ease of illustration.

*FIG. 1**FIG. 2**FIG. 3**FIG. 4**FIG. 5**FIG. 6**FIG. 7*
